UNITED STATES PATENT OFFICE

JOHN J. MULLIN AND JAMES L. FOLEY, OF DETROIT, MICHIGAN

VENTILATING APPARATUS

Application filed August 8, 1928. Serial No. 298,184.

This invention relates to ventilating apparatus and particularly to that type designed for use in connection with the kitchens of homes and like places, the principal object being the provision of a simple, efficient and economical apparatus by which the heat and odors of cooking may be removed from a room.

Another object is to provide a ventilating apparatus designed for insertion in the stack of a heating, cooking or other like apparatus.

Another object is to provide a ventilating apparatus adapted for insertion in the stack of a heating, cooking or other like apparatus comprising a casing having means for connection to the stack at one point thereon, and means for connection to the stack at another point thereon, the second means having a duct leading to and discharging within the first means, the casing being provided with an opening and means for drawing air into the opening from the room and forcing it through the first means into the stack, the construction being such that the air passing through the first means will cause a suction in the duct at the point of discharge of the duct therein.

A further object is to provide a ventilating apparatus of the type described comprising a casing provided with a collar adapted to be received in a flue and a second collar adapted to be connected to a stove or other apparatus, the second collar being provided within the casing with an extension forming a duct discharging within the first collar. This duct extends, without interruption, completely through said casing, the casing being provided with an opening and a motor provided with a fan disposed in the opening. The fan draws air into the casing and forces it into the flue, at the same time causing air to be drawn from the stove through the stack and discharged into the flue, by a "suction" effect, at the outlet of the mentioned duct, beyond the wall of said casing.

The above being among the objects of the present invention, the same consists in certain features of construction and combina-

tions of parts to be hereinafter described with reference to the accompanying drawing, and then claimed, having the above and other objects in view.

In the accompanying drawing which illustrates suitable embodiments of the present invention, and in which like numerals refer to like parts throughout the several different views,

Fig. 1 is a more or less diagrammatic side view showing a stove and a flue with a ventilating apparatus inserted in connection between the same.

Fig. 2 is an enlarged side view of the ventilating apparatus shown in Fig. 1 with parts thereof broken away to show the interior of the same in section.

Fig. 3 is a face view of a ventilator shown in Fig. 2.

Fig. 4 is a view similar to Fig. 2 showing a slightly modified construction.

Fig. 5 is a fragmentary sectional view illustrating a modified form of discharge collar for the ventilator shown in the previous views.

The ventilation of kitchens and like places has been the subject of considerable investigation in recent years. In hotels and in the higher class of homes hoods over the stove connected with a flue are usually provided during the construction of the building. However, when such hoods are not provided during the construction of the building, it is usually a difficult and expensive proposition to provide the same at later date. The usual method of ventilating a kitchen which has not been provided with a hood over the stove is to mount a fan in the transom over a door where such a door is provided leading to the outside of the building, or at the upper portion of a window opening, where no door to the outside is present. Either of these two last mentioned constructions have their advantages but at the same time they are usually located at a point relatively remote from the stove so that the grease from the stove and other vapors suspended in the air have ample time to come in contact with and be deposited on the walls and objects in the

room before reaching the fan. Furthermore, where the fan is positioned in the window, if curtains are used on the window, the grease-laden air is drawn into contact 5 with the curtains and soils them in very short time. In addition, when the fans are employed at the top of the window opening, it is usually impossible to completely close the window and the disadvantages 10 from this are readily apparent. Furthermore, in these constructions, if the wind is blowing against the fan, the ventilating effect of the fan is considerably impaired.

In accordance with the present invention 15 we provide a ventilating construction for use in those kitchens which have not originally been provided with ventilating hoods, and which construction retains all the advantages of a ventilating fan mounted 20 in a transom or window opening without being burdened with the disadvantages thereof, and which furthermore is not affected by the direction of the wind on the exterior of the building.

25 The manner in which this is accomplished will be apparent from a description of the drawing in which 10 represents a wall of a kitchen or other room on to which a flue 11 leading to a chimney opens. 12 is a 30 stove, illustrated as a gas stove for the purpose of explanation but which obviously may be a stove of any description. Ordinarily the stove 12 is directly connected to the flue 11 by a pipe as in conventional 35 constructions, but in the case of the present invention a ventilating device indicated generally as 13 in Fig. 1 is directly connected to the flue 11 and in turn is connected by a pipe 14 with the stove 12.

40 Referring to Figs. 2 and 3, it will be seen that the construction of the ventilator is as follows: A casing 13' which may be of any suitable contour, but which is shown substantially square, is provided with an integral rear wall 15 and an open front which is closed by a face member 16. The rear wall 15 is provided with a collar 17 which is adapted to be received in the flue 11 in the same manner that the conventional stove 45 pipe is received therein. The casing 13' may be further secured to the wall 10 by means of screws 18, inserted through flanges 19 projecting outwardly from the rear edge of the casing, and threaded into the wall 50 10. The bottom wall of the casing, as viewed in Figs. 2 and 3, is provided with a downwardly extending collar 20 adapted to be received in the pipe 14. Interiorly of the casing the collar 20 is continued as a 55 duct 21, decreasing in diameter from the collar 20, and extending to a point within the collar 17 at which point it is adapted to discharge into the collar 17, the duct 21 within the collar 17 being of sufficiently 60 small size as to permit ready flow of air

between the collar 17 and the duct 21. The forward wall 16 is provided with an opening bounded by an annular flange or collar 22 on the inside and a funnel-like wall portion 23 on the exterior. Suitably supported within the casing as by the bracket 24 and screws 25 is an electric motor 26, the axis of which is disposed in alignment with the center of the opening in the forward face 16 and shaft of which is provided with a fan 27 disposed within the collar 22. The outer edges of the fan preferably extend into relatively close contact with the inner walls of the collar 23. The electric motor 26 may be provided with wires such as 28 70 which extend downwardly to a point immediately above the stove 12 where they may be provided with a control switch such as 29, shown in Fig. 1, for the purpose of controlling the operation of the motor 26. 75

80 The operation of the above device will be readily apparent. When the electric motor 26 is running, air is drawn into the casing and discharged through the collar 17 about the duct 21 into the flue 11. The odors 85 from the stove as well as the particles of grease carried by the air from the stove are drawn into the casing and forced into the flue. Furthermore, the air in passing through the collar 17 about the duct 21 90 causes a suction in the duct 21 which draws the gases, smoke or other vapors from the stove through the pipe 14 and discharges them into the flue 11 with the same result as if the pipe 14 was directly connected to the flue 11 as in conventional constructions. 95

100 It will be apparent that with this device the operation of the stove is in no way impaired but in fact a greater draft may be supplied for the stove which will be beneficial particularly with coal or wood-burning stoves. Furthermore, the device may be located directly above the stove so as to draw the vapors from the stove into the same with the smallest amount of travel 105 through the room in which the stove is located. It will also be apparent that this device may be applied to any stove having a pipe connecting it with a flue, and that the operation of inserting the device in the 110 line of pipe is readily and easily accomplished by the ordinary householder. 115

120 Although this ventilating device may be formed of sheet or other metal, we prefer to form it of a molded material such as "bake-lite" or other moldable sound insulating material so that the noise of the motor will be reduced as much as possible. In such case we prefer to mold the casing 13' separate 125 from the cover 16 and to secure the latter thereto by screws such as 30 or other suitable means so that ready access to the interior of the casing is provided as well as greater ease in the molding operation. In any case the duct 21 may be not only 130

largest at its inlet end, from which it is shown as supported, and there continuous with the protruding collar 20, but molded as an integral part of a wall of the structure, although it will be apparent that any of the mentioned parts might be molded separately and afterwards secured in place.

In the construction shown in Figs. 2 and 3 the casing may be rotated about the axis 10 of the collar 17 in applying the device to a wall so that the pipe 14 may enter it from the bottom, sides or top, as will readily be apparent, thus providing means whereby the device may be inserted in a horizontal 15 or vertical line of pipe as found necessary. Where the stove is positioned a substantial distance away from the wall having the flue, the construction shown in Figs. 2 and 3 may be modified as shown in Fig. 4 so that the 20 pipe 14 may connect with it in a horizontal direction from the front face of the casing. In such a case, the collar 20 and duct 21 are not provided in the casing 13', but instead a front wall 31 is provided having the collar 22 and funnel-shaped portion 23 in the same manner as the wall 16, but further provided with a collar 32 projecting outwardly from the front face thereof for connection to the pipe 14. The collar 32 is provided with an inwardly extending duct portion 33 of substantially the same form as the duct 21 and exhausting into the collar 17 in the same manner.

Where a greater suction on the duct 21 or 33 leading from the stove is desired than is possible in the constructions shown in Figs. 2, 3 and 4, the collar 17 may be formed as indicated as at 34 in Fig. 5 in which the interior surface thereof is formed to provide a venturi. In any case the duct 21 or 23, as the case may be, preferably terminates at a point within the collar 17, which thus serves as the throat of a venturi, with the result that the lowered pressure at the throat increases the suction in the duct.

If desired, the efficiency of the device may be somewhat increased by providing a hood such as is indicated at 35 in Figs. 1 and 4. This hood may be made of sufficient size to overlie the top surface of the stove 12 and may be secured to the device as indicated in Fig. 4 by providing the rear edge thereof with flanges 36 which may be secured to the ventilator with the same screws 30 that hold the front face to the body of the casing. With this addition the device is as efficient as any hood provided as an original installation in the building without the necessity of any changes in the construction of the building whatsoever.

In the drawings the ventilator is shown supported directly against the wall 10, and this is usually preferable. However, it may 65 be desirable to support the same away from

the wall in some cases, or even to apply it directly to the stove. In such cases it is obvious that suitable pipes such as 14 may be employed to connect the collar 17 to the flue 11 and the results will be identical to those 70 herein described.

Although but a limited number of modifications of the present are shown in the accompanying drawing, it will be apparent that the same is subject to various modifications and changes without departing from the essential features disclosed, and these may take the form of various changes in the contour of the casing and arrangements of parts therein, and these and other formal 75 changes may be made in the specific embodiment of the invention described without departing from the spirit or substance of the broad invention, the scope of which is commensurate with the appended claims. 85

What we claim is:

1. In combination with a wall having a flue opening, and a stove, a casing secured to said wall provided with an opening, a collar bounding said opening received in said flue opening, said casing being provided with a second opening, a pipe connecting said second opening with said stove, a duct extending completely through said casing and into said collar and terminating therein, the end 95 of said duct within said collar being substantially smaller than said collar, and disposed favorably to a suction effect therein, and motor driven means independent of said openings for drawing air into said casing 100 and forcing it out of said casing between said collar and said duct into said flue, to produce said suction effect in that portion of said duct which is disposed within said collar. 105

2. In combination, a casing provided with an inlet opening and a discharge opening each provided with collars, said collar for said discharge opening being interiorly formed to provide a venturi, a duct connected with said inlet opening terminating in the throat of said venturi in generally spaced relationship with respect to the walls thereof, and motor driven means for drawing air into said casing independently of said inlet or discharge openings. 110

3. In combination, a casing provided with an outlet, a collar surrounding said outlet adapted for reception in a flue, a duct extending completely through said casing and so terminating at one end, within said collar and in generally spaced relationship in respect to the walls thereof as there to produce a suction effect, means for connecting the opposite end of said duct to a stove pipe, said casing being provided with an opening therein, a fan in said opening, a motor for driving said fan, and a hood carried by said casing overlying said opening. 115

4. In combination with a venturi formed 120

125

130

by a stove pipe and chimney flue, a casing surrounding said venturi, an opening in said casing and motor driven means drawing air into said casing through said opening and 5 forcing it out of said venturi.

5. A casing having three openings in the walls thereof, an uninterrupted duct extending completely through said casing between two of said openings, said duct being sealed 10 to said casing about one of said two openings and only partly obstructing the other of said two openings, a fan cooperating with the third of said openings, and means for driving said fan whereby to draw air into 15 said casing through said third opening and to force it out of said casing through said other of said two openings, thereby producing a "suction" from said duct, at a point beyond said casing.
20. 6. A ventilating device for use in combination with a stove pipe and stove flue and in which the stove pipe includes a duct whose outlet end is materially smaller than the stove flue and extends into the stove flue, 25 said device comprising: a casing sealed to and supporting an inward end of said duct at a point remote from said outlet end, said duct passing uninterruptedly through said casing and said casing being provided with 30 an inlet opening, a fan adjacent the opening, and a motor operating the fan,—whereby air is drawn through the opening and forced into the flue about the outlet end of said duct, for a suction effect therein.
